Primary Examiner — Steven J Czyz

(57) **CLAIM**

The ornamental design for a display stand, as shown and described.

DESCRIPTION

The patent or application file contains at least one drawing executed in color. Copies of this patent or patent application publication with color drawing(s) will be provided by the Office upon request and payment of the necessary fee.

1. Display stand

1.1: Bottom View

1.2: Front View

1.3: Rear View

1.4: Top View

1.5: Right Side View

1.6: Right Side Perspective View

1.7: Left Side Perspective View

Display stand for presenting a product to be applied to a fingernail.

1 Claim, 7 Drawing Sheets
(7 of 7 Drawing Sheet(s) Filed in Color)
